UNITED STATES PATENT OFFICE.

FRANK J. KRISTOFER, OF ST. PAUL, MINNESOTA, ASSIGNOR TO BROWN & BIGELOW, OF ST. PAUL, MINNESOTA, A CORPORATION OF MINNESOTA.

PENCIL-CLIP.

1,263,327.

Specification of Letters Patent. Patented Apr. 16, 1918.

Application filed June 27, 1917. Serial No. 177,372.

To all whom it may concern:

Be it known that I, FRANK J. KRISTOFER, a citizen of the United States, residing at St. Paul, in the county of Ramsey, and 5 State of Minnesota, have invented a new and useful Improvement in Pencil-Clips, of which the following is a specification.

My invention relates to pencil clips which are used to hold a pencil or pen in the user's 10 pocket and has as an object to provide a device which has a releasing button secured to a rigid arm and on which display matter can be illustrated.

This invention further comprises parts 15 formed from die stampings and which can be easily assembled for use.

These features together with other forms of construction will be more clearly defined and set forth in the following specifications 20 and claims:—

In the drawing, Figure 1 illustrates the pencil clip attached to a pencil.

Fig. 2 is a side elevation of the pencil clip attached to a pencil, a portion of the 25 barrel being broken away.

Fig. 3 is a central section taken through the pencil clip, a portion of the clip being shown in full lines.

Figs. 4, 5 and 6 are details of portions of 30 the pencil clip.

In the drawing, A represents a pencil clip which is adapted to be slipped on to the body of a pencil B and held in place by means of spring arms 1 formed on the 35 spring 2 of the pencil clip A. The spring arms 1 are formed on the cylindrical portion 3 of the spring 2 and practically encircle the pencil body when in use. The spring 2 is formed with a depressing finger 4 having a downwardly bent engaging end 5. The arms 1 are formed with circular openings 6 which are centrally positioned in the arms 1, thereby reducing the weight of the spring 2 and affording a better gripping means to 40 the arms 1.

A rigid arm 7 is adapted to be inserted through the opening 8 formed in the spring 2 and is formed with a semi-spherical cup-shaped engaging end 9 in which the engaging end 5 of the finger 4 is adapted to rest so as to hold the engaging end 9 against the body of the pencil or against the clothing when the pencil is inserted in the pocket.

The arm 7 is formed with an enlarged 55 portion 10 on the opposite end to the mem-

ber 9 and on which a button 11 is secured by means of engaging lugs 12 which are stamped out of the back 13 of the button 11 and bent upward so as to engage in the recesses 14 formed in either side of the enlarged portion 10 of the arm 7. The recesses 14 which are formed in the portion 10, form shoulders on either end of the recesses against which the lugs 12 engage, thereby preventing longitudinal movement of the 60 button.

The button 11 which is formed of any suitable material, has a display surface 15 on its outer side on which any suitable display can be printed.

The arm 7 is formed from a stiff piece of material having little or no resiliency and the engaging end 9 is adapted to slip through the opening 8, when the spring 2 and arm 7 are put together. The sides of 70 the straight shank 16 formed on the arm 7 are adapted to engage in the openings or slots 17 formed in the sides of the opening 8. The spring 2 being wider at the point where the opening 8 is formed to prevent 80 weakening the same by the hole 8 and slots 17. When the arm 7 is in position in the spring 2 and the engaging end 5 is inserted in the cup shaped end of the engaging member 9 of the arm 7 and the spring clip A 85 is slipped on to a pencil barrel, the member 9 will be held against the pencil barrel by means of the pressure of the spring finger 4. If it is desired to release the engaging member 9 from engagement with the surface of the pencil barrel, the button 15 is depressed, turning the arm 7 on its fulcrum point, which is formed by the slots 17 engaging the shank 16 and lifting or raising the end 9.

The spring 2 is formed from thin spring steel material so as to give sufficient resiliency to the spring finger 4. The engaging end 5 of the spring 4 locks the member 7 which carries the button 11 into engagement with the spring member 2 against displacement or disengagement from the same when the clip A is in position on a marking element.

The releasing button 11 prevents the engaging member 9 of the clip A from wearing on the clothing when the clip is in use on a pencil as the engaging end 9 can be disengaged from the pencil barrel automatically by the compression of the fingers 110

on the same when the pencil is inserted in the pocket and also when it is removed from the same. The releasing button also overcomes the necessity of holding the pocket or

5 clothing stiff when a pencil is inserted in the same. The releasing button also allows the use of a stronger spring member 2 and still affording easy insertion into the pocket.

10 The members 2 and 7 are formed entirely free and separate of each other but, in use of the clip A, are locked together by the end 5 engaging in the recess of the cup shaped engaging end 9. The rear portion of the arm 7 is held freely in place in 15 the slots 17. The opening 8 is formed so as to receive the semi-spherical engaging end 9 freely when the device A is assembled.

When the device A is disengaged from the pencil or marking element, the members 20 2 and 7 can be easily separated by disengaging the end 5 from the member 9 and withdrawing it through the opening 8, thus different buttons with various displays can be inserted in the same spring member 2 25 without necessitating changing the device or if one member of the device breaks it is only necessary to purchase or secure the broken member to make up a complete device.

30 The drawings illustrate a particular construction but I desire to have it understood that I do not wish to confine myself to this particular form, as the invention can be carried out by other means and applied to 35 uses other than those above set forth within the scope of the following claims:—

1. In a pencil clip, having a member 40 formed of spring material, arms formed on said member for resiliently engaging the barrel of a pencil, a rigid arm passing through said spring member, a semi-spherical engaging end formed on said arm, a spring finger formed on said spring member and an engaging end formed on said 45 spring finger adapted to engage said engaging end formed on said arm to lock said spring member and rigid arm together against disengagement.

2. In a device of the class described, 50 having a spring member, a cylindrical portion formed on said spring member for resiliently engaging the barrel of a marking element, a flat spring finger formed integral with said spring member extending longitudinally of said marking element, an in-turned engaging end formed on the free end of said finger, a rigid member passing through and under said spring member, a semi-spherical head formed on said rigid member in which said in-turned engaging end of said finger is adapted to engage and 55 slots in said finger forming a fulcrum point for said rigid member whereby one end of

said rigid member can be depressed to disengage the opposite end from said marking element against the pressure of said spring finger. 65

3. In a device of the class described, a spring element having engaging means to resiliently hold said spring element to the 70 body of a marking element, a spring finger formed integral with said spring element, an opening formed in said spring finger, a non-resilient element passing through said opening and extending longitudinally under 75 said spring finger, a semi-spherical hollow engaging head formed on said non-resilient element, an engaging end formed on the end of said spring finger which is adapted to engage in said head of said non-resilient 80 member to hold said head against the surface of said marking element by spring pressure and to simultaneously lock said spring element and non-resilient element together and a depressing button rigidly 85 held on the other end of said non-resilient member to disengage said head from said marking element.

4. In a device of the class described, a spring element for engaging about the barrel of a marking element, a spring finger extending from said engaging element, a non-resilient element extending through and under said spring finger, a semi-spherical hollow portion formed on one end of 95 said non-resilient element, an in-turned end formed on the end of said spring finger which is adapted to detachably engage in said hollow semi-spherical end formed on said non-resilient element and slots formed 100 on the free end of said non-resilient element which are adapted to hold a depressing button rigidly attached to the free end of said non-resilient member.

5. In a device of the class described, a 105 spring element having an engaging end for engaging the body of a marking element, a spring finger formed with said engaging element, a non-resilient element adapted to extend through said finger and under the 110 same, a semi-spherical hollow end formed on said non-resilient member, an in-turned end formed on said spring finger for freely engaging in said hollow semi-spherical end to depress the same, a semi-circular opening 115 formed in said spring finger and transversely extending slots extending from either side of said semi-circular opening formed in said finger, said slots forming fulcrum bearing points for said non-resilient element and said semi-circular opening 120 in said finger forming an opening so as to allow said non-resilient element to be inserted through said finger and extended under the same for the purposes specified.
